OIL TESTER

Donald S. Stoakes and Kenneth D. Brock, Minneapolis, Minn., assignors to Thexton Manufacturing Company, St. Louis Park, Minn.

Filed Oct. 6, 1971, Ser. No. 187,213

Term of patent 14 years

Int. Cl. D10—05

U.S. Cl. D26—1 Q

FIG. 1 is a left front perspective view of an oil tester showing our new design;

FIG. 2 is a right side elevational view thereof;

FIG. 3 is a top plan view thereof;

FIG. 4 is a bottom plan view thereof;

FIG. 5 is a front elevational view thereof; and

FIG. 6 is a rear elevational view thereof.

We claim:

The ornamental design for an oil tester, as shown and described.
